CLAIM

The ornamental design for a vehicle taillight as shown and described.

DESCRIPTION

FIG. 1 is a front and left side perspective view of a first embodiment of the vehicle taillight showing the present design;

FIG. 2 is a front, left side and top perspective view thereof; FIG. 3 is a front view thereof;

FIG. 4 is a left side view thereof;

FIG. 5 is a top view thereof;

FIG. 6 is a rear view thereof;

FIG. 7 is a right side view thereof;

FIG. 8 is a bottom view thereof;

FIG. 9 is a front and right side perspective view of a second embodiment of the vehicle taillight, the second embodiment being a mirror image of the first embodiment;

FIG. 10 is a front, right side and top perspective view thereof;

FIG. 11 is a front view thereof;

FIG. 12 is a right side view thereof;

FIG. 13 is a top view thereof;

FIG. 14 is a rear view thereof;

FIG. 15 is a left side view thereof; and,

FIG. 16 is a bottom view thereof.

1 Claim, 10 Drawing Sheets
